(57) **CLAIM**

The ornamental design for a display stand for bar tools, as shown.

DESCRIPTION

FIG. 1 is top view of display stand for bar tools showing my new design;

FIG. 2 is a side view thereof, the opposite side being a mirror image;

FIG. 3 end view thereof, the opposite side being a mirror image;

FIG. 4 is a bottom view thereof;

FIG. 5 is top perspective view thereof; and,

FIG. 6 is a bottom perspective view thereof.

The plate forming the top of the display stand for bar tools is lined for transparent material.

The broken lines depict portions of the display stand that form no part of the claim.

1 Claim, 6 Drawing Sheets(56)
